UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-END ASSEMBLY.

1,183,933.

Specification of Letters Patent.

Patented May 23, 1916.

Application filed March 31, 1915. Serial No. 18,388.

To all whom it may concern:

Be it known that I, JACOB H. WEISBROD, residing at 915 Olive street, St. Louis, Missouri, and being a citizen of the United States, have invented certain new and useful Improvements in Car-End Assembly, of which the following is a full, clear, and exact description, such as will enable others skilled in the art to which it appertains to make and to use the same, reference being had to the accompanying drawings which illustrate the preferred form of the invention, though it is to be understood that the invention is not limited to the exact details of construction shown and described, as it is obvious that various modifications thereof will occur to persons skilled in the art.

In said drawings: Figure 1 is an end view of the upper portion of a box car, with a portion of the end plate cut away, and showing the first carline next adjacent the end in elevation and the side plate and angle connecting the end plate to said carline in section. Fig. 2 is a section on line 2—2 of Fig. 5 looking toward the end showing the upper portion of the car. Fig. 3 is a perspective view of one-half of the end plate looking from the inside of the car, it being understood that said end plate is symmetrical. Fig. 4 is a plan view of a corner of the car with the roof removed showing the end plate, first carline and the connections between them. Fig. 5 is a vertical sectional view, the section being taken through the center of the car. Fig. 6 is a fragmentary detail sectional view, the section being taken on line 6—6 of Fig. 5, looking in the direction indicated by the arrow.

The object of the invention is to provide means primarily intended for reinforcing the ends of old box and stock cars, though it is to be understood that the invention is applicable also to new construction. Owing to violent buffing shocks, many such old cars are showing extreme weakness in their end construction and it is found necessary to reinforce the ends of such cars to retain them in service.

Another object of the invention is to provide a simple and economical single-sheathed end construction applicable to box and stock cars, in which the sides are of the ordinary type, that is, with outer sheathing and inner lining.

The invention contemplates the elimination at the end of such cars of the old wood

construction ordinarily consisting of end plates, end posts, braces, belt rails, cripple posts and outside sheathing, and substituting therefor a steel end frame, preferably of commercially rolled sections, with a single thickness of end lining boards secured to the inner faces of such commercial sections.

The end plate of the present invention, which is of pressed steel, is formed in a channel shaped section provided with a depending apron-like flange and attached flanges for connection to end posts and corner posts. The top flange of this end plate, is relatively narrow at the middle of the car and tapers, gradually widening until it reaches its maximum width at the portion of said flange adapted to overlie the side plates of the car. As the upper edge of the end plate is shaped to conform to the inclination of the roof, it is evident that in pressing such end plate with relatively narrow top flange at its middle portion, the metal which is taken from the vertical web to shape it to the inclination of the roof will provide a top flange of gradually increasing width toward the end of the end plate, assuming that a rectangular plate is employed. This gradually increasing width in the top flange is utilized in the present invention to provide a greater area of metal for the attachment of securing means herein-after described in detail.

In order to provide proper anchoring means for the end plate to the side frame of the car, angle shaped members are securely riveted to the top flange of such end plate and are bolted to the side plate, being also secured, as hereinafter described, to the first carline adjacent the end plate by suitable gusset connections. Near the longitudinal center of the car under the ridge pole, the end plate is also securely connected to said first carline by means of a flat bar.

The end plate is preferably formed from a single sheet of metal pressed into proper form, in which, in the drawings, 1 indicates the vertical web portion which is of maximum depth at its middle, 2 indicates the top flange inclined to the inclination of the roof and formed of minimum width at its middle portion, of gradually increasing width at its ends where the maximum width is attained and where the top flange overlaps the side plates 3 of the car with which it is connected by means of bolts 4 which pass through the vertical flanges 5, depending

from and preferably formed integral with the top flange 2^a of the end plate.

6—6 indicate angular members which may be either pressings or commercially rolled angles which extend under the wide end portions 2^a of the top flange 2 and are riveted thereto. Said angles extend at both sides of the car (though only one is shown in the drawings) parallel with the side plates, and as shown in Figs. 2 and 5, are bolted to said side plates by the bolts 4 and like bolts 4^a extending along and through the vertical legs of the angles 6 and through the side plates at convenient intervals.

15 Extending transversely of the car, as best shown in Figs. 4 and 5, is a carline 9, which may be of any suitable conformation in cross section, though in the present instance it is shown as of pressed channel shape with outstanding upper flanges 10, the carline being suitably connected to the side plates as is common in car construction. Connecting the angle 6 with the top flange of the carline 9 is a gusset plate 11 secured by suitable rivets 12 and 13 with the outer upper flange of the carline 9 and with the horizontal leg 6^a of the angle 6. Extending longitudinally of and below the ridge pole 15 is a rectangular plate 16 which extends under the middle portion of the flange 2 of the end plate where it is secured by rivets 17 to said flange and said plate 16 extends as best shown in Fig. 4 to and under the nearer of the flanges 10 of carline 9 to which it is connected by suitable securing means, as, for example, the rivet 18. The ridge pole 15 is likewise secured by bolts or other securing means 15^a with one of the flanges 10 of the carline 9 and with the middle portion of the top flange 2 of the end plate, thereby additionally securing the end plate to said carline. The end of the vertical web 1 of the end plate is partly cut away and partly bent to form the flange 21 which is in alinement 45 with the flange 5 before referred to, and like the flange 5 is bolted to the side plate by means of the bolts 4^a. The bottom of the vertical web 1 is bent to form the horizontal flange 20 and an apron 25 depending 50 from the flange 20, both of uniform width from end to end, and the apron lapping and being secured to the end sheathing 26^a. The end portion of apron 25 is bent outwardly at right angles to said apron portion and 55 forms a flange 26, which, as will be noted in Fig. 1, is connected by means of the bolt 27 with the corner post 28 of the car.

The bottom portion of the car end forms no part of the present invention and is not illustrated nor will it be described. Secured in any suitable manner at their bottom ends are intermediate posts 29 of Z-shape in cross section, the flanges 30 of which are connected by bolts 31 with the 65 sheathing 26^a before indicated. The posts

29 extend upwardly to and are connected with the horizontal flange 20 of the end plate by means of knee braces 32, which are connected by means of rivets 33 with the vertical web portion 34 of the members 29, 70 thus affording secure anchorage for the upper end of said posts. Posts 29 are secured to the flange 25 also by means of rivets 35. Supplemental to the posts and in close proximity to the corner posts, vertical rods 40 75 are provided, having heads 41 resting on the flange 20 of the end plate, and the opposite ends of said rods are suitably anchored to any convenient part of the underframing of the car.

80 By means of the peculiar conformation of the end plate coöperating with the angle 6, connection plate 16, gusset plate 11, connecting the angles 6 with the carline and the connection of the ridge pole before described, a very secure connection is afforded for the end plate with the roof and side framing of the car. With the end plate securely fastened, as indicated, a rigid bearing is provided for the upper ends of the 85 vertical posts 28 and 29 of the car ends, and the whole structure is admirably adapted to withstand shocks incident to shifting lading. Extending below the roof members 50 and secured to the vertical web of the end plate by bolts 51 is an end facia board 52 which additionally braces the end plate.

95 What I claim is:

1. A car end comprising, in combination, 100 end posts, sheathing, and an end plate of channel shape in cross section, said end plate being provided with a depending apron portion interposed between said posts and sheathing.

105 2. A car end comprising, in combination, end posts, sheathing, and an end plate of channel shape in cross section, said end plate being provided with a depending apron portion interposed between said posts and sheathing, and provided also with vertical flanges adapted to lap and be connected with car framing members.

110 3. In combination, corner posts, side plates, end posts intermediate said corner posts and a channel shaped end plate in 115 part vertically above said end posts and provided with vertical flanges lapping and being secured to said corner posts and side plate.

120 4. In combination, side plates, corner posts, end posts, a roof carline, a relatively channel shaped end plate having flanges secured to said side plates and flanges secured to said end posts, and angular members connecting said end plate, side plate and carline.

125 5. In combination, a reinforced car end portion comprising parts of side plates, a carline connecting said side plates; corner posts, end posts, a relatively channel shaped 130

end plate connected with said posts and with the side plates; connecting members extending parallel with and being secured to said side plates and means securing said connecting members with the end plate and carline.

6. In combination, side plates, corner posts, a carline, an end plate provided with flanges connected to said side plate and connecting members lapping said end plate, thence extending parallel with said side plate and being connected rigidly with said end plate, side plates and carline.

7. In combination, side plates, corner posts, a carline, an end plate provided with flanges connected to said side plate and corner posts and connecting members lapping said end plate, thence extending parallel with said side plate and being connected rigidly with said end plate, side plates and carline.

8. A car end comprising, in combination, end posts, sheathing, an end plate of channel

shape in cross section, said end plate being provided with a horizontal bottom flange 25 and a depending apron portion interposed between said posts and sheathing and means connecting said end posts to said horizontal flange, apron and sheathing.

9. In combination, corner posts, side 30 plates, end posts intermediate said corner posts, a flanged end plate in part vertically above said end posts and provided with vertical flanges lapping and being secured to said corner posts and side plate, a carline 35 connecting said side plates and short members rigidly secured to end portions and intermediate portions of said end plate and carline, thereby connecting the carline and end plate. 40

In witness whereof I have hereunto set my hand in the presence of two witnesses.

JACOB H. WEISBROD.
